Thomas W. Evans, of Philadelphia, Pa.
Letters Patent No. 1626, dated Aug. 12, 1862,

The schedule referred to in these Letters Patent and making part of the same,

To all whom it may concern:

Be it known that I, T. W. Evans, of Philadelphia, County of Philadelphia, State of Pennsylvania, have invented or produced a new and original design for Trade Mark; and I do hereby declare the accompanying drawing, with the following explanation of the same to form a full, clear and exact description of the said design.

On reference to the accompanying drawing, A, represents a vial upon the side of which is affixed the label B, containing the words "Hunts Bloom of Roses", which form the trade mark.

It is not necessary that the label should occupy the exact position upon the bottle as that shown in the drawing, or that it should be composed of a different material from that forming the vial, for the words may be stamped directly upon the vial or package containing the preparation; neither is it necessary that the vial should be of glass or of the exact form represented.

I claim a trade mark containing the words "Hunts Bloom of Roses", as described.

In testimony whereof I have signed my name to to this specification in the presence of two subscribing witnesses.
